AUDIBLE FIGURE TOY

Henry A. Blake, Newton, Mass., assignor to Blake Industries, Inc., Boston, Mass., a corporation of Massachusetts

Filed Nov. 2, 1959, Ser. No. 58,188

Term of patent 3½ years

(Cl. D34—2)

Fig. 1 is a front elevational view of an audible figure toy showing the new design;

Fig. 2 is a side elevational view thereof;

Fig. 3 is a top plan view thereof; and

Fig. 4 is a rear elevational view of the portion of the design shown in full lines.

The dominant features of the design reside in the portions shown in full lines.

I claim:

The ornamental design for an audible figure toy, substantially as shown and described.
